UNITED STATES PATENT OFFICE.

GEORGE F. REINTJES, OF KANSAS CITY, MISSOURI.

ARCH AND TILE FOR FORMING SAME.

Application filed August 25, 1926. Serial No. 131,444.

This invention relates to arches for furnace wall openings and the like and to units for the construction of such arches, and my object is to produce units whereby self-supporting arches may be erected without the use of mortar or any other binder. A further object is to produce units whereby it is possible to provide an opening with a self-supporting arch of such straight or curved form, or to arrange the arch units to provide a wall opening which slants or slopes in any desired direction. A still further object is to provide units and an arch therefrom of simple, strong, durable and inexpensive construction.

With these objects in view the invention consists in certain novel and useful features of construction and combinations of parts as hereinafter described and claimed; and in order that it may be fully understood, reference is to be had to the accompanying drawing, in which:—

Figure 1 is a front elevation of a self-supporting straight or horizontal arch composed of units embodying the invention.

Figure 2 is a similar view of a raised arch.

Figure 3 is a detail perspective view of one of the units.

Figure 4 is a detail perspective view of the other type of unit, which in conjunction with the unit shown in Figure 3 provides for an arch of any desired type.

Figure 5 is a side view showing a plurality of units as arranged to provide an opening which slopes or slants through a wall.

Referring now to the drawing in detail, 1 indicates an opening formed in a wall composed of fire brick 2 or the like. This opening, through the utilization of fire brick unit blocks, can be bridged horizontally or in an arch form, the arch units being indicated by the reference characters 3 and 4, the latter being primarily intended as key blocks.

The blocks 3, which form the major portion of the arch, are inclined at their side faces as at 5, the outer faces being upright or vertical by preference, and the inclinations of the side faces are parallel and correspond in all of the units. Said inclined faces are also of step form and by preference there will be several steps, three being illustrated. The tread portions of the bottom and intermediate step are of compound curved form as at 6 and the riser portions 7 are flat or straight and slightly inclined in the general direction of the inclination of

the side faces, the upper end of each riser portion of a step at one side of the unit being adapted to fit snugly into and interlock with the depending portion of the riser portion of an abutting block. The upper and lower faces of each block are horizontal and are provided with grooves 8 which are functionless when the arch is straight or horizontal as indicated by Figure 1, but which serve to receive and interlock with riser portions of abutting blocks when arranged to form a true arch, as indicated in Figure 2.

The key unit blocks correspond in height and in width from front face to rear face 70 with the unit blocks 3, and at one side are inclined and stepped as described by reference to the unit blocks 3, that is to say, are stepped as at 10 to correspond to the tread portions 6 and have riser portions 11 corresponding to riser portions 7 of unit blocks 3. The other face of each key unit block is flat as at 12, and extends at right angles to the top and bottom faces of such blocks, which like the top and bottom faces of unit blocks 3 are horizontal.

To produce a straight or horizontal arch, a pair of the unit blocks are mounted upon the wall 2 at opposite sides of the opening 1. These unit blocks are preferably of the key type for convenience of laying other brick 2 conveniently against them because of the straight outer sides of the key unit blocks. If a block such as 4, is mounted upon the wall 2 at each side of the opening, 85 blocks 3 are also mounted preferably upon such walls with their outer step portions or sides interlocking with the inner or step sides of blocks 4, it being preferred that the first of the blocks 3 employed shall 90 partly overlap the opening. Additional blocks 3 are then successively placed in interlocking relation until the opening is sufficiently bridged from each side to accommodate a pair of the key blocks, it being un-

derstood, of course, that the proportion of the opening from one side to the other and of the width of the blocks will be determined prior to the placement of the blocks 4, so that when the key blocks are fitted 105 between, and interlocked with the innermost blocks 3, the opening shall be completely closed and the flat or vertical sides 12 of the key blocks shall fit snugly together. In the building of this arch, which can be 110 accomplished by unskilled labor, and without the use of mortar or the like, temporary

supports, not shown, can be utilized as a support for the blocks as they are progressively placed in position inwardly from the sides of the opening 1, and when the key blocks are placed in position, the arch is wholly self-sustaining and the temporary supports are removed. Where narrow openings are spanned, the operator can place the unit blocks in position without necessitating the use of supports, at least any other support than by use of a hand. For the erection of the blocks in an arch form as illustrated by Figure 2, the same procedure is followed, except that certain of the blocks, progressively inward, will be arranged in gradually ascending planes; each step in the ascent corresponding to the height of a step or riser, and the upper ends of the lower steps of the blocks thus arranged in different horizontal planes will enter the lower recesses 8 of the adjacent blocks in higher planes, and the lower ends of the upper steps of the higher blocks will fit in the recesses 8 in the tops of the next lower abutting blocks, all as illustrated in Figure 2.

Where it is desired to bridge or span the upper side of an opening in a wall 1, inclined or sloped, and is of width or thickness to accommodate a plurality of a series of the blocks arranged side by side, the different series of the blocks will start at different levels so that the opening shall extend upwardly and inwardly or downwardly and inwardly accordingly, as indicated in Figure 5, the blocks of each series interlocking together to span the opening as explained with reference to Figure 1 or Figure 2, according as the arch is to be horizontal or of a true arched character, the unit blocks of the arch forming a support for the ordinary brick to continue the erection above the opening, such brick work or blocks being indicated in dotted lines by the character 13.

From the above description, it will be apparent that I have produced unit blocks by which arches of any span, straight or of true arched character, can be readily erect-

ed or constructed by unskilled labor and without use of mortar or any other binder, and the blocks are of such character that only two types are needed, namely, the blocks 3 and the blocks 4, as by simply reversing their position they can be used at either side of the center of the opening span. In other words, all of the ordinary blocks 3 are identical and may be produced from a common mold, and this statement applies with reference to the key blocks 4.

It is apparent that the blocks may be made with a single step or with a plurality of steps as indicated, and that the blocks are susceptible of modification in minor particulars without departing from the principle of construction and mode of operation involved or from the spirit and scope of the appended claims.

I claim:

1. A unit block for arch construction having parallel inclined faces of step form, the steps at one side being inverted with respect to the steps at the opposite side, the top of the block adjacent the upper end of the top-most riser having a transverse groove, and the bottom of the block adjacent the lower end of the undermost riser, having a corresponding groove or recess.

2. The combination of a series of blocks arranged to form an arch which slopes upwardly and inwardly from each side, certain of the blocks at opposite sides of the center of the arch being disposed in different horizontal planes, and said blocks having inclined side faces of step-like form, the abutting stepped faces of adjacent blocks being interlocked together against independent horizontal movement, all of the blocks standing in overlapping relation, the two innermost blocks having abutting flat faces and constituting key blocks for the arch as a whole.

In witness whereof I hereunto affix my signature.

GEORGE P. REINTJES.
